UNITED STATES PATENT OFFICE

93,531

DESIGN FOR A MAGNETIC COMPASS

Erich Bandoly, Rochester, N. Y., assignor to
Taylor Instrument Companies, Rochester, N. Y.,
a corporation of New York

Application July 27, 1934, Serial No. 52,716

Term of patent 14 years

To all whom it may concern:

Be it known that I, ERICH BANDOLY, a citizen of the United States of America, residing at Rochester, in the county of Monroe and State of New York, have invented a new, original, and ornamental Design for a Magnetic Compass, of which the following is a specification, reference being had to the accompanying drawing wherein:

Fig. 1 is a front view of a magnetic compass showing my new design;

Fig. 2 is a side view; and

Fig. 3 is a rear view thereof.

I claim:

The ornamental design for a magnetic compass, as shown.

ERICH BANDOLY.
